UNITED STATES PATENT OFFICE.

HENRY H. AKERS, OF CHERRYVALE, KANSAS, ASSIGNOR TO H. H. AKERS MANUFACTURING COMPANY, OF CHERRYVALE, KANSAS.

MAIL-BAG CATCHER AND DELIVERER.

No. 893,966.

Specification of Letters Patent. Patented July 21, 1908.

Application filed November 25, 1907. Serial No. 403,787.

To all whom it may concern:

Be it known that I, HENRY H. AKERS, a citizen of the United States, residing at Cherryvale, in the county of Montgomery and State of Kansas, have invented a new and useful Mail-Bag Catcher and Deliverer, of which the following is a specification.

This invention relates to mail bag catching and delivering apparatus of that general class shown and described in United States Letters Patent issued to me on the 13th day of February 1906 under No. 812471.

The object of the invention is generally to improve and simplify the construction of both the track crane and car device thereby to increase their efficiency as well as to reduce the cost of manufacture.

A further object of the invention is to provide improved means for retaining the bag retaining jaws of the car device in open or operative position, and means for automatically releasing the jaw carrying arm from engagement with the car when said jaws are moved to closed or inoperative position.

A still further object is to reinforce and strengthen the track crane by constructing the swinging bag supporting frame of angle iron and further to render the latter more positive and efficient in operation by the employment of coiled springs for moving said frame laterally to inoperative position.

Further objects and advantages will appear in the following description, it being understood that various changes in form, proportions and minor details of construction may be resorted to within the scope of the appended claims.

In the accompanying drawings forming a part of this specification: Figure 1 is a top plan view of the apparatus of the present invention. Fig. 2 is an elevation of the apparatus in readiness to transfer mail bags. Fig. 3 is a detail longitudinal sectional view of the operating lever of the car device.

Fig. 4 is a side elevation of the auxiliary bag supporting arm of the car device. Fig. 5 is a sectional view of the spring actuated catch for locking the swinging bag supporting arm in engagement with the car. Fig. 6 is an end elevation of the bag delivery arm of the car device. Fig. 7 is a longitudinal sectional view showing the construction of the sliding arm of the track crane. Fig. 8 is a front elevation of the bag supporting member or stationary device of the track crane. Fig. 9 is a

transverse sectional view of the lower crane arm showing the fingers for supporting the guy chains.

Similar numerals of reference indicate corresponding parts in all of the figures of the drawings.

The improved mail bag catcher and delivering apparatus of the present invention includes a stationary track device or crane comprising spaced standards 5 and 6 preferably formed of spring metal and having their lower ends threaded in suitable base plates 7 mounted on a masonry foundation 8, preferably formed of concrete, as shown.

The standards 5 and 6 are rigidly supported in spaced relation to each other by suitable clamps 9 and 10 one of which constitutes a cap and is provided with a socket 11 for the reception of the adjacent trunnion of a swinging bag supporting frame 12, there being a similar bearing 13 formed in the lower clamp 9 and adapted to receive the lower trunnion of said swinging frame.

The frame 12 is formed of angle iron, preferably T shaped in cross section, and includes spaced upper and lower horizontally disposed arms 14 and 15 connected by a vertical bar 16, the upper arm 14 of the swinging frame being extended laterally beyond the vertical arm 16 to form a support for a casting or bracket 17. The casting or bracket 17 is secured to the free end of the upper arm 14 by screws or similar fastening devices 18 and is provided with spaced transverse openings or apertures for the reception of parallel rods 19 and 20 between which is supported the mail bag to be delivered to a passing car. The upper bar or rod 20 is extended rearwardly and inwardly to form inclined braces 21, the free ends of which are bolted or otherwise rigidly secured to the upper arm 14, as indicated at 22. It will thus be seen that the rod 20 and integral braces 21 form in effect a substantially tri-angular frame.

The free ends of the bars or rods 19 and 20 are spaced apart to form spring arms which are normally held in parallel relation to each other by means of suitable rings or loops 23 which bear against stop lugs or pins 24 carried by the upper bar 20.

Detachably secured to each ring 23, as by a hook 25 is a chain, cable or other flexible medium 26 having a coiled spring 27 secured thereto and fastened to suitable eyes 28 carried by the clamp or cap piece 10, said springs

105

110

serving to swing the bag supporting frame laterally to a position substantially parallel with the track 29 when the mail bag 30 is delivered to a passing car, in the manner hereinafter described.

Depending from the lower arm 15 of the swinging frame is a casing or housing 31 in which is slidably mounted an arm or bar 32, the free end of which terminates in a horizontally disposed bag engaging jaw 33 the opposite ends of which are preferably deflected laterally, as shown. The movable bag engaging jaw 33 co-acts with a similar stationary bag engaging jaw 34 preferably formed integral with the casing or housing 31, said movable jaw being normally and yieldably retained in contact with the stationary jaw by means of a coiled spring 35 one end of which is secured to the adjacent end of the arm 32 while the opposite end thereof is secured to a pin or bolt 36 engaging a correspondingly threaded lug 37.

By adjusting the pin in the lug 37 the tension of the spring 35 may be regulated so as to vary the pressure exerted by the movable jaw on the stationary jaw when said jaws are moved to closed or inoperative position.

As a means for holding the movable jaw in open position there are provided suitable trip levers 38 each having angularly disposed arms one of which extends between the jaws 33 and 34 and in the path of the mail bag 39 carried by the car 40, the opposite arm of each trip lever being pivoted at 41 on the stationary jaw 34 and provided with a terminal operating handle 42.

Depending from the sliding arm 32 is a handle 43 by means of which the movable jaw 33 may be moved outwardly in spaced relation to the stationary jaw 34. It will thus be seen that when the trip levers 33 are in the position shown in Fig. 1 of the drawings the mail bag 39 on the car will strike the arm of the adjacent trip lever and swing the same inwardly thus causing the spring 35 to draw the jaws together and grip the bag.

The movable jaw 33 is provided with a vertical extension or arm 44 having a spring clip secured thereto and adapted to engage the adjacent ring of the bag 30 thereby to assist in holding said bag in convenient position to be engaged by the car device.

The stationary track device or crane is preferably reinforced and strengthened by an inclined brace 45 which extends between the standards 6 and an anchoring block 46 similar in construction to the block 8, there being inclined braces 47 disposed one on each side of the block 8 and extending between the clamp 9 and suitable anchoring blocks 48.

The car device comprises a horizontally disposed arm 49 preferably formed of metal and constructed in two sections to produce an intermediate chamber for the reception of a sliding bar 50.

The inner or pivoted end of the arm is provided with a tubular socket 51 which receives the pivot pin of a bracket 52 carried by the car, there being a loop 53 fastened on one side of the arm 49 and to which is secured the adjacent end of a coiled spring 54, the opposite end of the spring being fastened to an eye or staple arranged on the inside of the car. 70

The free end of the bar or arm 50 is provided with a bag engaging jaw 55 which contacts with a relatively stationary jaw 56 secured to the free end of the arm 49, there being a trip arm or catch 57 pivotally mounted for swinging movement on the stationary arm 56 and similar in construction and operation to the trip levers 38 of the track device. 75

Secured to the outer face of the jaw 55 is a tubular socket or casing 58 in which is pivotally mounted a horizontally disposed rod 59 one end of which is formed with an eye 60 80 while the opposite end thereof is bent upon itself and extended outside the casing 58 to form an arm 61 adapted to receive and support the mail bag 39 of the car device.

Pivoted in the eye 60 is a ring 62 which engages the free end of the rod 61 and serves to prevent accidental displacement of the bag 39. 90

The sliding bar 50 is provided with a longitudinally disposed slot 63 which registers 95 with a corresponding slot 64 formed in the casing constituting the arm 49, and pivotally mounted at 65 on the bar 50 is an operating lever 66 having its lower end pivoted at 67 to an arm or bracket 68 depending from 100 the arm 49, as shown.

The operating lever 66 is formed with an elongated slot 69 so as to allow free play of the operating lever when the latter is moved to the dotted line position shown in Fig. 3 of 105 the drawings. A coiled spring 70 connects the operating lever 66 with a lug or bracket 71 on the arm 49, the normal tendency of said spring being to retract the lever.

As a means for holding the arm 49 in operative position on the bar there is provided a locking member or catch 71 having its inner end pivoted at 72 in a casing or housing 110 preferably countersunk in the car frame and having its outer end provided with a terminal inclined face 73 adapted to engage the head 74 of a spring pawl 75.

The pawl 75 is disposed within the chamber of the arm 49 and in the path of movement of the bar 50 so that when the bar 50 is 120 moved inwardly, said bar will engage and elevate the head 74 of the pawl and thus elevate the locking member 71 so as to permit the coiled spring 54 to move the arm 49 and its associated parts to inoperative position 125 within the car.

Disposed at the juncture of the stationary jaw 56 and arm 49 is a socket 76 adapted to receive a depending rod 77 having its free end bent laterally and provided with a ter- 130

terminal clip or catch 78 adapted to engage the lower portion of the mail bag or sack 39 and thus assist in retaining said bag in position to enter the jaws of the track device or crane.

The stationary jaw 34 of the track device or crane or crane as well as the stationary jaw 56 of the car device are each formed with an elongated slot 79 so as to permit the adjacent trip levers to clear the movable jaws 33 and 10 55 when the latter are forced in engagement with the stationary jaws by the action of the coiled springs.

As a means for steadyng the movable frame of the track crane and preventing the same from swinging laterally by the action of the wind when a mail bag is in position for delivery, there are provided suitable guy chains or cables 80 each having one end thereof anchored to the adjacent block 48 and its opposite end provided with a terminal ring or loop 82 adapted to engage a hooked finger 83 depending from an arm 84 secured to the stationary jaw 34.

The free ends of the arms 84 are provided with vertical pins 85 one of which is adapted to engage the terminal ring of one of the guy chains when the ring of the other chain is in engagement with the adjacent depending finger.

30 Secured to the handle 43 is a transverse bar 86 having its opposite ends bifurcated to produce spaced fingers 87 the ends of which are bent laterally, as shown, and adapted to disengage the adjacent ring 82 from the contiguous finger 83 when the movable jaw 33 is released.

When the track crane is positioned to deliver a mail bag the operator places the terminal ring 82 of one of the guys over the pin 40 85 of the adjacent arm 84 and the ring of the opposite guy over the terminal fingers of the handle 43, and forces the latter outward to open the jaws 33 and 34.

As the handle 43 is moved longitudinally of the arm 31 the ring on the fingers 87 will pass over the hooked terminal of the adjacent depending finger 83 and thus retain said ring in position on the finger 83, and in which position the guy chains 80 and 81 will prevent swinging movement of the pivoted frame of the crane by the action of the wind.

When the movable jaw 33 is released the spring 35 will cause the fingers 87 on the handle 43 to disengage the adjacent ring 55 from the hooked terminal of the contiguous depending finger 83 thus permitting the spring 27 to swing the movable frame laterally to a position substantially parallel with the track, as will be readily understood.

60 In practice, the mail bag 39 is suspended from the rod 61 of the car device and the latter swung outwardly with its free end projecting beyond the side of the car and in which position it is securely held by the
65 catch 71, in the manner before described.

The bag 30 is then placed in position between the rods 19 and 20 of the track device or crane with its lower end engaging the clip of the arm 44 after which the rings 23 are moved laterally in engagement with the stop lugs 24 so that the tension of the springs 27 will be exerted equally on each end of the substantially triangular frame 21 of the crane and thus maintain the swinging frame of the latter in a position substantially at right angles to the track. 75

As the car approaches in the direction indicated by the arrow in Fig. 1 of the drawings the mail bag 39 of the track device will engage and trip the adjacent lever 38 thus causing the spring 35 to move the movable jaw 33 to closed position and secure the bag 39 on the crane, the handle 43 in its rearward movement automatically releasing one of the guy chains 80, in the manner before described. At the same time the bag 30 will engage the trip lever 37 of the car device and detach said bag from the rods 19 and 20, the mail bag in its forward movement disengaging the adjacent ring 22 which latter slides over the curved corners of the triangular frame 21 to the rear of said frame thus causing the spring 27 connected with the opposite ring to swing the bag supporting frame of the crane laterally to a position substantially parallel with the track, as before stated, and in which position the mail bag 39 may be readily detached from the clamping jaws 33 and 34 by exerting a longitudinal pull on the handle 43.

When the trip lever 57 is moved to released position by the impact of the mail bag 30, said trip lever will swing laterally within the slot 79 so as to permit the spring 70 to draw the bar 50 of the car device within the 105 chamber of the arm 49.

As the bar 50 moves inwardly the free end of the bar will engage and elevate the locking device or pawl 75 which in turn will release the catch 71 thereby permitting the 110 spring 54 to swing the arm 49 carrying the mail bag 30 within the car.

In setting the device the operating lever 66 is moved in the direction of the stationary jaw 56 and the trip lever 57 swung outwardly until the free end thereof engages the adjacent surface of the movable jaw 55 and in which position the car device is again ready to receive a mail bag from the track device or crane. 115 120

From the foregoing description it is thought that the construction and operation of the device will be readily understood by those skilled in the art and further description thereof is deemed unnecessary. 125

Having thus described the invention what is claimed is:

1. In a mail bag catching and delivering apparatus, a car device mounted to swing into and out of the car, stationary and mov- 130

- able bag engaging jaws forming a part of the car device, means for locking the car device in engagement with the car, a pawl carried by the car device, a trip lever for holding the jaws in operative position, and a spring actuated bar secured to the movable jaw and adapted to engage the pawl and release the locking device when the trip lever is actuated.
2. In a mail bag catching and delivering apparatus, a car device mounted to swing into and out of the car, stationary and movable bag engaging jaws forming a part of the device, means for locking the car device in engagement with the car, a spring actuated bar carrying the movable jaw, an operating lever operatively connected with the sliding bar, and a pawl arranged in the path of movement of said bar and actuated by the latter to release the locking means.
3. In a mail bag catching and delivering apparatus, a car device mounted to swing into and out of the car, stationary and movable bag engaging jaws forming a part of the car device, there being a slot formed in the stationary jaw, a trip lever pivotally mounted for swinging movement in said slot and adapted to engage the movable jaw, said trip lever being actuated by the impact of a mail bag thereby to operate the jaws.
4. In a mail bag catching and delivering apparatus, a car device mounted to swing into and out of the car, stationary and movable bag engaging jaws forming a part of the device, one of said jaws being provided with an elongated slot, a trip lever pivotally mounted for swinging movement within the slot and adapted to engage the adjacent jaw, a spring actuated bar secured to the movable jaw, a lever for moving said jaw to open position, means for locking the car device in engagement with the car, means disposed in the path of movement of the bar and actuated by the latter for releasing the locking means, and means for automatically swinging the car device laterally within the car when the trip lever is actuated.
5. In a mail bag catching and delivering apparatus, the combination with a car, an arm mounted to swing horizontally into and out of the car and provided with an interior chamber, a stationary bag engaging jaw secured to the free end of the arm, a bar slidably mounted within the chamber and provided with a similar jaw, a trip lever pivotally mounted on one of the jaws and adapted to engage the adjacent jaw for holding the jaws in spaced relation, a lever pivotally mounted on the arm and pivotally connected with the sliding bar, means for locking the arm in engagement with the car, a pawl disposed in the path of movement of the bar and actuated by the latter to release the locking means, and a spring connecting the lever with the arm.
6. In a mail bag catching and delivering apparatus, the combination with a car, of a hollow arm pivotally mounted within the car and provided with a relatively stationary bag engaging jaw, a bar slidably mounted within the arm and provided with a jaw co-acting with the stationary jaw, means carried by one of the jaws for suspending the mail bag, a trip lever pivotally mounted on the opposite jaw and including angularly disposed fingers one of which is adapted to engage the adjacent jaw, the opposite finger being extended to form an operating handle, a lever pivotally mounted on the arm and pivotally connected with the bar, means for locking the arm in engagement with the car, a pawl extending in the path of movement of the bar and actuated by the latter to release the locking means, and means for automatically swinging the arm within the car when the trip device is actuated.
7. In a bag catching and delivering apparatus, the combination with a car, of a hollow arm pivotally mounted for swinging movement on the car and provided with a relatively stationary bag engaging jaw, a bar slidably mounted within the arm and provided with a similar jaw, means carried by said jaw for suspending a mail bag therefrom, a bracket depending from the arm, an operating lever pivotally mounted on the bracket and provided with a longitudinal slot, a pin extending through said slot and connecting the lever with the sliding bar, means for locking the arm in engagement with the car, and a spring pawl arranged in the path of movement of the bar and actuated by the latter to release the locking means when the jaws are actuated.
8. In a mail bag catching and delivering apparatus, the combination with a car, of a hollow arm pivotally mounted for swinging movement on the car and provided with a relatively stationary bag engaging jaw, a bar slidably mounted within the arm and terminating in a similar jaw, a bracket depending from the arm and provided with means for engagement with a mail bag, a lever pivotally mounted on the arm and having a pin and slot connection with the sliding bar, means for locking the arm in engagement with the car, means disposed in the path of movement of the bar and actuated by the latter to release the locking means, a spring secured to the interior of the car and connected with the pivoted end of the arm for automatically swinging said arm within the car when the jaws are actuated.
9. In a mail bag catching and delivering apparatus, the combination with a car, of an arm pivotally mounted for swinging movement on the car and provided with a relatively stationary jaw, a bar slidably mounted on the arm and terminating in a similar jaw, a rod secured to one of the jaws and having

- one end thereof provided with an eye and its opposite end bent to form a rod for engagement with a mail bag, a ring pivotally mounted in the eye and adapted to receive 5 the adjacent end of the rod, a lever pivotally mounted on the arm and having a pin and slot connection with the sliding bar, means for locking the arm in engagement with the car, and means arranged in the path of 10 movement of the sliding bar and actuated by the latter to release the locking means when the jaws are moved to closed position.
10. In a mail bag catching and delivering apparatus, the combination with a car, of an 15 arm pivotally mounted for swinging movement on the car and provided with a relatively stationary bag engaging jaw, a bar slidably mounted on the arm and terminating in a similar jaw, one of said jaws being 20 formed with an elongated slot, an angularly disposed trip lever pivotally mounted in the slot and adapted to engage the adjacent jaw, a bracket depending from the arm, an operating lever having a pin and slot connection with the sliding bar, a lug spaced from the bracket, a spring forming a yieldable connection between the lug and lever, means for locking the arm in engagement 25 with the car, means disposed in the path of 30 movement of the sliding bar and actuated by the latter to release the locking means, and means for automatically swinging the arm and its associated parts within the car when the trip lever is actuated.
- 35 11. In a mail bag catching and delivering apparatus, the combination with a car, of an arm pivotally mounted for swinging movement on the car and provided with a relatively stationary bag engaging jaw having a 40 slot formed therein, a bar slidably mounted on the arm and provided with a jaw co-acting with the stationary jaw, a trip lever pivotally mounted in the slot and adapted to engage the movable jaw, there being an opening formed in the arm, a bracket slidably mounted within the opening and provided with means for engagement with a mail bag, means for locking the bracket in adjusted 45 position, an operating lever having a pin and slot connection with the sliding bar, a catch secured to the car, a spring pawl disposed in the path of movement of the sliding bar and actuated by the latter to release the catch, and means for swinging the arm with- 50 in the car when the trip lever is actuated.
- 55 12. In a mail bag catching and delivering apparatus, the combination with spaced standards, a frame pivotally mounted for swinging movement on one of the standards and provided with means for supporting a bag, a stationary bag engaging jaw secured to the frame, a bar slidably mounted on the frame and provided with a similar jaw, a spring connected with the sliding bar, means 60 extending from one of the jaws for engagement with a mail bag, and springs forming a connection between the opposite sides of the swinging frame and the standards.
13. In a mail bag catching and delivering apparatus, a support, a substantially rectangular frame pivotally mounted for swinging movement on the support, a triangular frame carried by the rectangular frame, a rod spaced from the triangular frame and disposed parallel with one wall thereof, said rod 70 and triangular frame being adapted to receive a mail bag between the same, pins extending from the triangular frame, rings slidably mounted on said frame and adapted to bear against the pins, springs connecting the rings with the support, relatively stationary and movable bag engaging jaws carried by the rectangular frame, and a trip lever pivotally mounted on one of the jaws and adapted to engage the adjacent jaw for holding 75 said jaws in open position.
14. In a mail bag catching and delivering apparatus, the combination with a support, of a frame pivotally mounted for swinging movement on the support, a relatively stationary jaw carried by the frame, a bar slidably mounted on the frame and provided with a similar jaw, one of said jaws being 80 formed with an elongated slot, an angularly disposed trip lever pivotally mounted in the slot and having one end thereof arranged to engage the adjacent jaw and its opposite end 85 terminating in an operating handle, a spring secured to the sliding bar, means for regulating the tension of the spring, means carried 90 by the swinging frame for supporting a mail bag, and yieldable means disposed on opposite sides of the swinging frame and connected with the support.
15. In a mail bag catching and delivering apparatus, the combination with a support, of a frame pivotally mounted for swinging movement on the support, a rod secured to the upper portion of the frame and having its 95 opposite ends bent inwardly and rearwardly for attachment to the adjacent portion of the frame, pins extending laterally from said rod, a second rod spaced from the pin carrying rod and adapted to support a mail bag, rings slidably mounted on the opposite ends 100 of said rods and adapted to engage the pins, bag engaging jaws carried by the swinging frame, and yieldable means forming a connection between the rings and the support, said rings being movable laterally on the inclined portions of the rod when the mail bag 105 is detached from said rod.
16. In a mail bag catching and delivering apparatus, the combination with spaced standards of different heights and connected 110 by clamps each formed with a socket, a swinging frame pivotally mounted in said sockets, a rod secured to the frame and bent 115

into a substantially tri-angular form, pins secured to said rod, a second rod spaced from the bag carrying rod and forming a support for a mail bag, rings slidably mounted on said rods and adapted to engage the pins, springs forming a connection between the rings and the adjacent sides of the swinging frame, bag engaging jaws carried by the frame, anchoring members spaced from the standards, and braces connecting the standards with said anchoring members.

17. In a mail bag catching and delivering apparatus, the combination with a support, of a frame mounted for swinging movement on the support and provided with relatively stationary and movable gripping jaws, guys secured to the stationary jaw, and means carried by the movable jaw for releasing one of the guys when said jaw is moved to closed position.

18. In a mail bag catching and delivering apparatus, the combination with a support, of a frame mounted for swinging movement on the support and provided with relatively stationary and movable jaws, guys secured to the stationary jaw, an operating handle depending from the movable jaw, means carried by the operating handle and adapted to disengage one of the guys when the jaw is moved to closed position, and means for swinging the frame laterally when the guy is released.

19. In a mail bag catching and delivering apparatus, the combination with a support, of a frame mounted for swinging movement on the support and provided with relatively stationary and movable jaws, fingers depending from the stationary jaw, pins carried by the fingers, spaced guys one of which is adapted to engage the adjacent finger and the other the adjacent pin, means carried by the movable jaw for releasing the guy from the depending finger when the movable jaw is moved to closed position, and means for au-

tomatically moving the frame laterally when said guy is released.

20. In a mail bag catching and delivering apparatus, the combination with a support, of a frame mounted for swinging movement on the support and provided with relatively stationary and movable jaws, arms extending laterally from the stationary jaw and provided with vertically disposed pins, fingers depending from the arms and having hooked terminals, guys disposed on opposite sides of the stationary jaw and provided with terminal rings one of which is adapted to engage the hooked terminal of the adjacent depending finger, the ring of the other guy being adapted to engage the pin of the adjacent finger, a handle depending from the movable jaw, means carried by the handle for releasing the adjacent ring from the hooked terminal, and means for automatically moving the swinging frame laterally when the ring is released.

21. In a mail bag catching and delivering apparatus, the combination with a support, of a frame mounted for swinging movement on the support and provided with relatively stationary and movable gripping jaws, guys detachably secured to the stationary jaw, a handle carried by the movable jaw, oppositely disposed fingers secured to the handle and adapted to engage one of the guys for releasing the latter from engagement with the stationary jaw when the movable jaw is moved to closed position, and means for automatically swinging the frame laterally when said guy wire is released.

In testimony that I claim the foregoing as my own, I have hereto affixed my signature in the presence of two witnesses.

HENRY H. AKERS.
